UNITED STATES PATENT OFFICE

2,433,712

WRIST STRAP

Kenneth E. Shearon, Wilmette, Ill.

Application February 12, 1945, Serial No. 577,517

7 Claims. (Cl. 24—77)

1

This invention relates to wrist bands suitable for wrist watches and the like and particularly a wrist band suited to fabrication from thin, resilient, flexible sheet material.

Wrist bands of the type in consideration, made from thin, resilient sheet material such as stainless steel, because of the absence of the usual pliability of leather and other often used materials, are in many instances provided with buckles which are complicated, unusual in operation, and not readily operable. It is an object of the present invention to provide in a metallic strip band, a buckle that is extremely simple, easy to operate in a manner readily understood, and which is comfortable to wear and not unduly stiff at the buckle.

Another object of the invention is to provide a buckle and strap which may be readily stamped from ordinary thin resilient sheet metal or like material and thereafter economically assembled.

A further object of the invention is to provide a buckle and strap which is pleasing in appearance and not bulky, and which may be taken off or placed upon the wrist of the wearer by the simple sliding of the ends into overlapping position.

The above and other novel features of the invention will appear more fully from the following detailed description when taken in conjunction with the accompanying drawings. It is expressly understood, however, that the drawings are employed for purposes of illustration only and are not designed as a definition of the limits of the invention, reference being had for this purpose to the appended claims.

In the drawings wherein similar reference characters refer to similar parts throughout the several views:

Figure 1 is a perspective view of the wrist band as it would appear when worn on the wrist,

Figure 2 is a side elevation of the buckle,

Figure 3 is a top plan view of the buckle,

Figure 4 is a bottom plan view of the buckle, and

Figure 5 is a side elevation of the buckle with the ends separated.

Referring to the drawings and particularly to Figure 1, the strap will be seen as composed of two strap members 10 and 12, joined through a watch 14, through the rolled loops 16 and 18. The straps may be made of noncorrosive metal such as stainless steel, having resiliency, but also capable of being deformed to closely conform to the contour of the wearer's wrist. The strap members are adapted to be overlapped and secured

2

together in any desired position by reason of a novel buckle, generally indicated at 19.

In order to render the strap adjustable lengthwise at the buckle, the tongue portion 20 of the strap 10 is perforated by a series of apertures 22, through any one of which a hook 24 may be projected. The hook 24, is formed on the end of a narrow longitudinally extending finger or strip 26, having at its other end a transverse flat collar 28, slideably arranged upon the tongue 20. The hook is sufficiently small to be readily extended through any one of the apertures 22 and may be resiliently flexed or slightly inclined to facilitate such insertion.

The hook 24 is adapted to reach through one of the apertures 22 only a sufficient distance to receive easily the thickness of the metal from which the buckle frame 30 is formed. The buckle frame 30 is rectangular in shape with a rectangular opening 31, and is secured along one of its edges to the strap 12 in a rolled eye 32 suitably formed and flattened to smoothly receive the buckle, so that the buckle when in position, as shown in Figure 2 lies as nearly flat as possible, taking into consideration that the tongue 20 is extended therethrough. The buckle is bent or offset at 34 to facilitate the nesting of the parts, the offset providing a flat lying portion engaging the hook 24, and a portion extending diagonally across the tongue 20 to the rolled eye 32 on the end of the strap member 12, as shown in Fig. 2. A sleeve 36 is slidably arranged on the strap 12, and is adapted to be telescoped over the tongue 20, up toward the rolled eye 32 to clamp the strap 12 and tongue 20 lightly together and hold all the parts in buckled relation.

The ease with which the parts may be buckled together and released is shown in Figure 5. By sliding the sleeve 36 to the right, the straps may be moved toward one another to allow the buckle to be released from the hook 24 and lifted slightly, after which the parts are readily separated. To clasp the parts together it is only necessary to extend the tongue 20 through the buckle window 31 and thereafter hook the buckle 30 on the hook 24, after which the sleeve 36 is moved to the position shown in Figure 2.

The hook 24 may have been previously positioned in the proper aperture to provide the degree of snug fit desired by the wearer. The parts, in assembling, approach one another in practically their normal buckled position permitting the operation previously described without danger of pinching or producing any discomfort whatsoever. The band may be worn more snugly for this rea-

son. At no point are there more than two layers of overlapped metal for any distance so that flexibility is not seriously impaired, and once the band is formed or molded to fit the wearer, by springing the metal beyond its elastic limit, the fit is so perfect and the weight so slight that the wearer is hardly conscious of its presence.

It will be readily apparent that all the parts are readily formed from thin sheet metal if desired. Also, if desired, the hook sleeve 28, and telescoping sleeve 36, may be soldered or otherwise secured where the ends meet, as seen in Figure 4. However, the sleeves should have a sliding fit neither too loose nor too tight, so that once positioned, they will remain in such position.

Although but a single modification of the invention has been shown and described, it is to be understood that various alterations and changes in proportion and selection of material may be made without departing from the spirit of the invention, as will be well understood by those skilled in the art. Reference will therefore be had to the appended claims for a definition of the limits of the invention.

What is claimed is:

1. A buckle for securing wrist watches and the like to the arm, comprising a pair of thin, flexible resilient wrist band end members adapted to partially overlap one another and to be secured together in overlapped relation, one of said members having an end tongue and a series of perforations longitudinally arranged therealong, a slideable collar arranged upon said member having a finger extending along the underside of said member, and said finger having a hook formed in the end thereof adapted to be projected through any selected perforation a sufficient distance to constitute a hook on the upper side of said member, and the other of said members having a substantially rectangular buckle frame pivoted at the end thereof, said frame being adapted to receive said tongue and to slide therealong and to engage said hook, and a sleeve, slideable on said buckle carrying member adapted to be slid along said member and over the said end tongue of the first mentioned member.

2. A buckle for securing wrist watches and the like to the arm, comprising a pair of thin, flexible resilient wrist band end members adapted to partially overlap one another and to be secured together in overlapped relation, one of said members terminating in a tongue and having an outward and rearwardly extending hook short of the end thereof, and the other member having a substantially rectangular buckle frame pivoted at the end thereof and adapted to receive said tongue, and to slide therealong to engage said hook, and a sleeve slideable on said buckle carrying member adapted to be slid along said member and over the said end tongue of the first mentioned member to hold the members in light, resilient engagement thereby resisting loosening of the buckle.

3. A buckle for securing wrist watches and the like to the arm, comprising a pair of thin, flexible resilient wrist band end members adapted to partially overlap one another and to be secured together in overlapped relation, one of said members having an end tongue and a series of perforations longitudinally arranged therealong, a slideable collar and finger arranged upon said member, and having a hook formed in the end of said finger adapted to be projected through any selected perforation, the other of said members having a substantially rectangular buckle

frame pivoted at the end thereof, said frame being adapted to receive said tongue and to slide therealong and to engage said hook, and a sleeve slideable on said buckle carrying member adapted to be slid along said member and over the said end tongue of the first mentioned member to hold the members in light resilient engagement thereby resisting loosening of the buckle.

4. A buckle for securing wrist watches and the like to the arm, comprising a pair of thin, flexible resilient wrist band end members adapted to partially overlap one another and to be secured together in overlapped relation, one of said members terminating in a tongue and having an outward and rearwardly extending hook short of the end thereof, and the other member having a substantially rectangular buckle frame stamped from sheet material, one edge of which is received in a flattened rolled eye formed in the end of the member, and the other edge of which is adapted to be passed over said tongue to engage said hook, said frame being bent slightly along a central transverse line, to provide a portion to lie flat on the outside of said tongue, and a portion to extend diagonally across said tongue and pass beneath said tongue.

5. A buckle for securing wrist watches and the like to the arm, comprising a pair of thin, flexible resilient wrist band end members adapted to partially overlap one another and to be secured together in overlapped relation, one of said members terminating in a tongue and having an outward and rearwardly extending hook short of the end thereof, and the other member having a substantially rectangular sheet material buckle frame, one edge of which is received in a flattened rolled eye formed in the end of the member, and the other edge of which is adapted to be passed over said tongue to engage said hook, said frame being bent slightly along a central transverse line, to provide a portion to lie flat on the outside of said tongue, and a portion to extend diagonally across said tongue and pass beneath said tongue, and a sleeve, slideable on said buckle carrying member adapted to be slid along said member and over the said end tongue of the first mentioned member.

6. A buckle for securing wrist watches and the like to the arm, comprising a pair of thin, flexible resilient wrist band end members adapted to partially overlap one another and to be secured together in overlapped relation, one of said members having an end tongue and a series of perforations longitudinally arranged therealong, a slideable collar and finger arranged upon said member, and having a hook formed in the end of said finger adapted to be projected through any selected perforation, and the other of said members having a substantially rectangular buckle frame pivoted at the end thereof, said frame being adapted to receive said tongue and to slide therealong and to engage said hook, said frame being bent slightly along a central transverse line to provide a portion to lie flat on the outside of said tongue, and a portion to extend diagonally across said tongue and pass beneath said tongue, and a sleeve, slideable on said buckle carrying member adapted to be slid along said member and over the said end tongue of the first mentioned member.

7. A buckle for securing wrist watches and the like to the arm, comprising a pair of thin flexible resilient wrist band end members adapted to partially overlap one another and to be secured together in overlapped relation, one of said mem-

bers terminating in a tongue and having a series of perforations arranged centrally and along the length thereof, and the other member having a substantially rectangular buckle frame stamped from sheet metal to form a frame having side portions and transverse portions, one transverse portion of which is received in a rolled eye formed in the end of the member, and the other transverse portion of which is wider than said first named transverse portion and is adapted to be passed over said tongue, means cooperating with said wider portion of said frame and one of said perforations to resist movement of said frame along said tongue, said side portion of said frame being bent slightly to enable said last named wide portion to lie flat on the outside surface of said tongue, and said side portions to extend diagonally across the edges of said tongue and with the one transverse portion beneath said tongue, and a slidable flat sleeve on the other member adapted to be slid over said tongue toward said rolled eye, and adapted to snugly en-

gage and hold said members flat against one another.
